Taiwanese Notice of Allowance mailed Mar. 8, 2017 for Taiwanese Design Patent Application No. 105306585, 3 pages.

Primary Examiner — Lauren Calve(74) *Attorney, Agent, or Firm* — Jackson IPG PLLC; Demian K. Jackson(57) **CLAIM**

The ornamental design for a knob, as shown and described.

DESCRIPTION

FIG. 1 is a perspective view of a knob showing my new design;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof; and,

FIG. 7 is a bottom plan view thereof.

The broken lines shown represent unclaimed subject matter and form no part of the claimed design.

1 Claim, 4 Drawing Sheets(56)
